(57) **CLAIM**

The ornamental design for a LED flashlight, as shown and described.

DESCRIPTION

FIG. 1 is a front top right-side perspective view for a LED flashlight, showing my new design;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof;

FIG. 6 is a top plan view of FIG. 1 thereof; and,

FIG. 7 is a bottom plan view of FIG. 1 thereof.

The part of the photographs shown in a coarser dot pattern

within the broken-line perimeter as well as the broken-line

(Continued)

perimeter itself, illustrates a portion of the LED flashlight that forms no part of the claimed design.
